Attorney

UNITED STATES PATENT OFFICE.

JOSEPH F. FULLOP, OF CHRISTOPHER, ILLINOIS.

TOOL FOR REMOVING WELL CASINGS AND THE LIKE.

Application filed August 24, 1921. Serial No. 495,034.

To all whom it may concern:

Be it known that I, JOSEPH F. FULLOP, a citizen of the United States, residing at Christopher, in the county of Franklin and 5 State of Illinois, have invented certain new and useful Improvements in Tools for Removing Well Casings and the like; and I do hereby declare the following to be a full, clear, and exact description of the invention, 10 such as will enable others skilled in the art to which it appertains to make and use the same.

This invention relates to certain new and useful improvements in tools for removing 15 pipe, such for example as casings from drill holes and the like.

It is an object of my present invention to produce a relatively small, compact, and at the same time an easily operated tool, which 20 can be readily positioned within a casing or pipe for withdrawing and salvaging the same.

Another object of my invention is the production of a tool provided with a novel 25 gripping section and an associated device for controlling the movement of the gripping means and locking same in inoperative position, thereby facilitating the removal of the tool from the casing should for any 30 reason it be found impracticable to remove the pipe sections forming the casing.

A further object of the invention is to produce a tool provided with a pipe gripping section detachably associated with a 35 supporting section, both of said sections being hollow and arranged to house the controlling connections for the gripping devices.

A still further object of my invention is 40 the production of a tool of the class referred to, consisting of a series of detachable and interchangeable sections, arranged and adapted to permit of the control of the gripping device from a source remote from 45 the tool.

Other objects will in part be obvious, reference being had to the specification and the accompanying drawings, in which:—

Fig. 1 is a side elevation of my improved 50 tool showing the gripping devices locked in retracted or inoperative position;

Fig. 2 is a vertical sectional view through my tool taken at right angles to Fig. 1, and further illustrating the positions of the grip-

ping devices when associated with a pipe or 55 casing, the latter being conventionally indicated in dotted lines;

Fig. 3 is a sectional elevation of one of the detachable sections of the tool used to increase the weight thereof, the lower or cap 60 end being shown threaded thereon; and

Fig. 4 is a horizontal sectional view on the line 4—4 of Fig. 2 showing the gripping devices in elevation and extended or operative position. 65

Referring to the drawings, in which similar reference characters designate corresponding parts in the several views, my improved tool is formed of complementary sections, termed for purposes herein the gripping section 1, and the top or supporting section 2. The sections are preferably of 70 hollow, cylindrical contour and are detachably joined together by means of the nipple connection 3.

Gripping devices in the form of normally protruding dogs or fingers 4 are carried by the gripping section 1. The gripping dogs are pivotally supported at 5 in recessed or open portions 6 formed in the cylindrical 80 wall of the section 1, and arranged and adapted to be normally projected outwardly by means of springs 7. The ends of the gripping dogs or fingers are tapered and suitably provided with a gripping face or 85 edge designed to either bite into the well casing or engage the lower edge of a pipe section thereof. As shown in the drawings there are two groups of three gripping dogs each, the respective groups being staggered 90 so as to insure a uniform gripping action of the casing as will be understood. I believe this to be a satisfactory arrangement of the gripping dogs, although it will be understood that other arrangements can be 95 provided without departing from the spirit of my invention.

The springs 7 are secured at 8 to the inclined upper faces of the slotted openings or recesses 6, the extending arm of the spring 100 bearing against the gripping dogs as shown. The tapered end of the gripping dog together with the positioning of the spring serves to permit the withdrawal of the gripping dogs from operative to inoperative position and substantially flush with the outer face of the gripping section. 105

The means for controlling the withdrawal

of the gripping dogs includes the connections 9, each of said connections having one end connected to an eye 10 secured to the respective gripping dogs, and the other end 5 secured to an operating connection arranged within the hollow cylindrical section comprising the tool.

A link 11, formed with eyes 12 and 13 to which latter some of the opposite ends of the 10 connections 9 are secured, constitute a portion of the aforesaid operating connection. The link connection or rod 14 forms another portion of this operating connection, said rod 14 being provided with an eye 15 to 15 which the upper eye 13 of the link 11 is connected, as well as the opposite ends of the other connections 9 of some of the gripping dogs as clearly shown in Fig. 2.

The means for locking the gripping dogs 20 in closed or inoperative position will now be described.

The upper end of the rod or link connection 14 is formed with a screw threaded portion 16 upon which is threaded a nut 17. 25 Spring arms 18 are secured to the upper end of the supporting section 2 in diametric relation, said arms being provided with clamping portions 19 arranged and adapted to bear against the threaded portion 16 of 30 the rod, but at the same time permitting of the movement of the rod when occasions require. When it is desired to withdraw the gripping dogs to inoperative position the cable 21 connected to the eye 20 formed in 35 the end of the rod 14, is pulled upwardly, the nut 17 spreading and passing between the spring arms 18 until said nut has been moved to a position above the clamping portions 19, whereupon these clamping portions 40 19 spring inwardly and bear against the threaded portion 16 and prevent the return of the nut in a reverse direction. With the gripping dogs in this locked position as shown in Fig. 1 the tool can be readily re- 45 moved from the casing or drill hole.

This construction is particularly advantageous where in some cases it is impossible to remove the casing, and after having lowered the tool, it also becomes impossible to 50 remove the tool. By the present construction the possibility of the loss of the tool is reduced to a minimum.

In practice, and before the tool is lowered, the nut 17 is adjusted upon the threaded portion 16 beneath the spring arms 18 according to the distance through which the gripping dogs must be moved to securely lock them in inoperative position.

This adjustment having been made, the 60 tool is lowered into the casing and the gripping dogs allowed to engage the pipe.

The supporting section 2 of the tool is provided with the rods 22, the lower ends of which are threaded into the upper face of 65 the section 2, and the upper ends of which

are offset and brought together to form eyes 23 to which the hoisting cable 24 is attached.

In Fig. 3 I have shown a filler section 25 suitably threaded so as to be easily attached between, or preferably beneath the gripping section 1. When it is desired the tool can be quickly weighted by inserting one or more of these sections, without affecting the operation of the tool or materially 75 delaying the progress of the work. A cap closure section 26 is shown threaded upon the filler section 25. When but two sections are used this cap section is attached to the threaded extension 27 formed on the gripping section 1 as will be understood, thereby increasing the penetrating efficiency of the tool should there be mud or other substances found within the drill hole.

I claim:

1. A gripping tool of the class described comprising a support, a gripping device including jaws carried by said support adapted to extend outwardly therefrom, operating means connected to said gripping device and adapted to extend from the interior of a well in which the tool is placed to a position above the ground surface, said operating means being also adapted to move the gripping device into inoperative position to 95 permit retracting the tool, and means for automatically locking said gripping device in operative position when the operating means is actuated to move the gripping device into inoperative position. 100

2. A gripping tool of the class described comprising a support, gripping means movably associated with said support, means including a cable extending from said tool for moving said gripping device into inoperative position, and means carried by the tool for automatically locking the gripping device in said inoperative position, said means for moving the gripping device being operated at a point remote from the tool. 105

3. A gripping tool of the class described comprising a support, a gripping device carried by said support and movable into inoperative position to permit retracting the tool, and means including a spring for automatically locking the gripping device in the aforesaid inoperative position when said gripping device is moved into its inoperative position. 115

4. A well tool including a support, gripping elements mounted on said support and adapted to move outwardly from said support into operative position, operating means for drawing said elements toward said support and into inoperative position, and automatically actuating locking means adapted to automatically secure the operating means in the position it occupies when holding the gripping elements are in inoperative position. 120

125 130

5. A gripping tool of the class described comprising a support formed of complementary sections detachably joined together, a gripping device carried by one of said sections, said gripping device being arranged and adapted to normally engage the work, operating means for moving the gripping device into inoperative position and means carried by the other of said sections for automatically locking said gripping device in inoperative position when said operating means is actuated to move the gripping device into inoperative position.
10. A gripping tool comprising a tubular support, gripping jaws pivotally mounted on said support and adapted to be moved outwardly into operative position, a rod axially movable within said support, means connecting the rod to said jaws, operating means connected to said rod and adapted to extend from the ground surface to the tool while the latter occupies a position within a well, and locking means adapted to automatically lock the rod in one position after 25 the rod has been drawn into said position by the operating means.
15. A gripping tool including a tubular section having threaded ends, pockets arranged in the periphery of said section, jaws pivotally connected to said section and adapted to occupy said pockets when in inoperative position, a second section in threaded connection with the first section and provided with locking elements, operating means for drawing said jaws into said
- 20 pockets, and a member mounted on said operating means and engageable with said locking elements for automatically locking the jaws in inoperative position when said operating means is moved to bring the jaws 40 into inoperative position.
25. A gripping tool of the class described comprising a support, a gripping device detachably associated with said support for normally engaging the work, means for moving the said gripping device into inoperative position, means for locking the gripping device when moved into inoperative position, and an adjusting device for determining the relative movement of the 45 gripping device when being locked in the aforesaid inoperative position.
30. A gripping tool of the class described comprising a support formed of complementary sections detachably joined together, a gripping device carried by one of said sections for normally engaging the work, means for moving said gripping device into inoperative position, means carried by the other of said complementary sections for locking the gripping device when moved into inoperative position, and means including another section detachably joined to the aforesaid complementary sections.
35. In testimony whereof I affix my signature, 55 in presence of two subscribing witnesses.
- JOSEPH F. FULLOP.
